UNITED STATES PATENT OFFICE.

ANTHONY A. BRUNSWICK, OF SAN FRANCISCO, CALIFORNIA.

DESIGN FOR A BUTTON.

SPECIFICATION forming part of Design No. 21,449, dated April 5, 1892.

Application filed December 28, 1891. Serial No. 416,839. Term of patent 3½ years.

To all whom it may concern:

Be it known that I, ANTHONY A. BRUNSWICK, a citizen of the United States, residing at San Francisco, in the county of San Francisco and State of California, have invented and produced a new and original button design to be worn as a souvenir button on the lapel of a coat or vest or on the apparel where it may be most desirable, of which the following is a specification, reference being had to the accompanying drawings, forming a part thereof.

Figure 1 is a somewhat exaggerated view of button design; Fig. 2, a view of button design as worn on the lapel of coat, these views being deemed necessary to fully illustrate my design.

The leading feature in my design consists in a button having the representation of a navel orange with stem and leaf attached, forming the top or body part of a button

joined to a shank having a head or holding piece, as seen in Fig. 1.

A represents a navel orange; b, the stem; c, the leaf growing out from the stem over 25 and upon the orange and resting itself there; d, scroll for inscription; e, characteristic navel mark of the orange, and f the shank part of button, the parts entire forming a souvenir-button design having the navel orange as the 30 leading feature of the design. The shank and head of same attached to the button design are shown in the drawings.

What I claim, and desire to secure by Letters Patent of the United States, is—

The design for a button, as herein described and shown.

ANTHONY A. BRUNSWICK.
